UNITED STATES PATENT OFFICE.

JOHN PENCE POWELLS, OF CINCINNATI, OHIO.

LOCK.

Application filed October 19, 1923. Serial No. 669,602.

This invention appertains to door locks and the primary object of the invention is the provision of an improved means for locking a door, whereby the possibility of 5 the door being broken open or unlocked by unauthorized persons is reduced to a minimum.

Another prime object of the invention is the provision of a novel lock for an outside door of a residence or the like embodying a pair of locking bolts and novel means for permitting the free operation of the locking bolts from the inside of the door, so that the door can be readily opened from 10 the inside, the improved lock having no means carried by the outside of the door for permitting the operation of the lock, the means for permitting the operation of the lock being hidden in one side of the 15 door frame.

A further prime object of the invention is the provision of an improved door lock having the means for permitting the opening of the lock from the outside of the door 20 hidden in one side of the door frame, the mentioned side of the door frame being provided with a hinged cover plate normally held in a closed position by a key operated lock, the operating means for permitting the 25 opening of the door from the outside thereof being also closed by a hinged panel, said panel normally hiding from view a pair of manually operable switches, which are so disposed as to be readily operated by 30 unauthorized persons, when such persons endeavor to raise the hinged panel, thereby closing an alarm circuit.

A further object of the invention is the provision of an improved door lock having 35 the operating means for the lock for permitting the opening of the door from the outside hidden in a suitable casing located at one side of the door frame, the improved door lock embodying a pair of locking bolts and an operating arm for actuating the bolts, the operating arm extending through the door and into said casing, the operating means embodying a bolt for engaging said arm to cause the actuation of 40 the locking bolts.

With these and other objects in view, the

invention consists in the novel construction, arrangement and formation of parts as will be hereinafter more fully described, claimed, and illustrated in the accompanying drawings, in which drawings:

Figure 1 is a front elevation of a door and door frame with the improved locking mechanism incorporated therewith.

Figure 2 is a similar view showing the 60 panels of the door removed and parts of the door broken away to illustrate the improved lock incorporated therewith, the hinged door and panel for the casing at one side of the door frame being shown removed 65 to illustrate the operating mechanism.

Figure 3 is an enlarged fragmentary front elevation of the side of the door frame having the casing for the operating mechanism lock incorporated therewith, parts of 70 the casing being shown broken away.

Figure 4 is an enlarged fragmentary vertical section through the casing formed in parts of the door frame, parts of the hinged panel and cover being shown broken away. 75

Figure 5 is an enlarged fragmentary vertical longitudinal section through the front rail of the door illustrating the locking bolts carried thereby and the means for holding the bolts in their inoperative non-locking position.

Figure 6 is a fragmentary edge elevation of the door, showing the slide plate carried by the door for preventing the locking bolts from protruding through the door 80 when so desired.

Figure 7 is a detail horizontal section taken on the line 7—7 of Figure 5 illustrating the operating means for the slide plate, and

Figure 8 is a detail vertical section taken on the line 8—8 of Figure 2 illustrating the means for operating the locking bolts from the inside of the door.

Referring to the drawings in detail, 95 wherein similar reference characters designate corresponding parts throughout the several views, the letter A generally indicates a door and B a door frame therefor. The door A has incorporated therewith the improved locking means C, while the door frame B has incorporated in a portion there-

of novel means D for facilitating the opening of the door from the outside thereof.

While the door A can be of any preferred construction, the same preferably includes inner and outer rails 10 and 11, and top and bottom rails 12 and 13. These rails are preferably covered by a suitable paneling or the like 15. Arranged between the panels 15 are disposed horizontal supporting bars 16, 17 and 18. As shown the supporting bar 17 is located at the transverse center of the door and intermediate the bars 16 and 18.

The door frame B is constructed as near as possible as ordinary door frames and in accordance with the invention, the portion of the door frame located at the inner or pivoted edge of the door A is provided with a built-in casing 20 having a hinged cover 21 which finishes off the casing and presents to the view of the casual observer an ordinary door post. This cover 21 can be held closed against unauthorized opening movement by a suitable key operated lock or the like 22.

25 The operating means D of the lock C is located in the casing 20, as can be clearly seen by referring to Figures 2, 3 and 4 of the drawings.

30 The improved lock C of the door A comprises a pair of upper and lower sliding locking bolts 25 and 26, which extend through the outer end rail 11 of the door and these bolts are normally urged through the rail, by suitable contractile coil springs 35 27, which have their outer ends connected to the inner ends of the bolts and their opposite ends to the rails 11. It is obvious that these springs normally tend to urge the bolts 25 and 26 outward of the door A in engagement with the keeper openings 28 formed in one side of the door frame B.

In order to hold the door in an unlocked position, so that free access may be had to the house with which the door is associated 45 during the daytime, a slide plate 29 is provided. This slide plate 29 is mounted on the free outer edge of the door A and is held in place against accidental displacement by suitable headed pins or screws 30, which are mounted in slide guideways 31 formed in the slide plate 29. The inner face of the slide plate 29 is provided with an enlarged rack bar 32, which is mounted in a recess portion of the rail 11. This rack bar 32 has meshing therewith a sector pinion 33 keyed to a suitable door knob shank 34 the opposite ends of which extend through the opposite faces of the door and have keyed thereto operating door knobs 35 and 60 36. The slide plate 29 adjacent to its opposite ends is provided with openings 37 for permitting the bolts 25 and 26 to engage their keepers 28 but it is obvious that when the slide plate 29 is operated by one of the 65 door knobs 35 or 36, that the plate can be

slid so as to move the openings 37 from out of alignment with the bolts and thus prevent the locking movement of said bolts.

The bars 16 and 18 support operating levers 40 and 41, which are mounted at points 70 equidistant their ends upon suitable pins 42 carried by said supporting bars. The outer ends of these levers 40 and 41 are pivotally connected to the locking bolts 25 and 26, while the inner ends thereof are pivoted as 75 at 43 to the terminals of a connecting bar 44. This connecting bar 44 has rigidly secured thereto in any preferred way the locking arm 46 which is provided with a longitudinally extending slotted guideway 47 for 80 the reception of the guide blocks 48 secured to the supporting bar 17. One edge of the operating arm 46 is provided with a rack bar 49 having meshing therewith a sector pinion 50 which is keyed to a suitable operating shaft 51. This operating shaft 51 protrudes through the inner face of 85 the door A and has connected therewith an operating door knob 52. Thus it is obvious that on the turning of the door knob 90 52, the operating arm 46 can be operated which will in turn manipulate the levers 40 and 41 and retract the bolts 25 and 26 thus permitting the opening movement of the door. As the door knob 52 is located on 95 the inside of the door, it is obvious that the door can be readily opened from the inside thereof.

The operating connecting rod 44 also has connected thereto the inwardly extending rigid operating bar 53, which extends through the inner rail 10 of the door for a purpose, which will be hereinafter more fully described.

The means D for operating the locking 105 means C from the exterior of the door comprises a sliding operating arm or bolt 60, which is provided with a longitudinally extending slotted guideway 61 for the reception of the guide block 62. The upper edge 110 of this bolt or operating arm 60 is provided with a rack face 63 having meshing therewith a sector pinion 64. This sector pinion 64 is secured to a suitable operating shaft 65, having mounted thereon a door knob 66. 115 This door knob 66 can be provided with any preferred type of operating key 67 so as to permit the locking thereof to the shank or shaft 65 and thus permit the manipulation of the operating arm or bolt 60. The forward end of this arm or bolt 60 extends through the inner walls of the casing 20 for engagement with the inner edge of the operating bar 53 and it is obvious that when the operating bolt 60 is manipulated that 125 the same will engage the operating bar 53 and thus cause the retracting of the bolts 25 and 26 which will permit the opening of the door.

As stated the casing is normally closed by 130

the cover 21, and in order to further prevent access of the casing to be had by authorized persons, I provide a hinged panel 70. The lower edge of this hinged panel 70 can be provided with a combination lock 71 if so desired, the locking bolt of which can engage a keeper 72 carried by one end wall of the casing 20. The panel 70 is hinged at its upper edge to a suitable partition plate 73 disposed in the casing 20. Arranged in the casing 20 adjacent to the lower edge of the panel 70 is a pair of spaced partition plates 74 and 75, and these partition plates carry the manually operated switches 76 and 77, which can be of any preferred type or character. These switches 76 and 77 are so disposed, that should access be gained into the casing 20 by unauthorized persons by opening the hinged cover 21, when the said unauthorized persons try to open the hinged panel 70, the switches 76 and 77 will be operated and thus close a circuit. The switch 77 preferably controls the alarm circuit, which can lead to any distant place so as to give an effective alarm. The other switch controls the lighting of an incandescent lamp 78 arranged in the casing 20 and its switch 76 is adapted to be closed, by authorized persons opening the door, so as to permit such persons to readily see to open the door.

From the foregoing description, it can be seen that I have provided an exceptionally simple and efficient door lock, which will practically prevent unauthorized opening of doors or residences and the like.

Changes in details may be made without departing from the spirit or the scope of this invention.

40. What I claim as new is:

1. The combination with a door frame and a door hingedly connected thereto, of a lock for the door including a pair of reciprocating locking bolts, resilient means normally urging the bolts outward of the door into engagement with the frame, means carried by the free edge of the door and operated from either side of the door for normally lying in the path of said bolts for permitting the engagement of the bolts with the door frame, means for permitting the operation of the bolts from the inside of the door and means located in the door frame at the outside of the door for operating said bolts.
2. The combination with a door and door frame, of a door lock comprising a pair of locking bolts arranged to engage the door frame, spring means engaging the bolts for normally urging the frame outward of the door, and a pair of pivoted operating levers rockably mounted at a point equidistant from their ends on the door, means pivotally connecting the outer ends of the levers to the inner ends of the bolts, an operating rod

connecting the inner ends of the levers together, an operating arm reciprocably carried by the door, and a door knob associated with the inner face of the door for operating said arm.

3. The combination with a door and door frame, of a lock for the door comprising a pair of reciprocating bolts, resilient means for normally urging the bolts outward of the door in engagement with the door frame, a pair of pivoted operated levers rockably mounted at a point equidistant from their ends upon the door, means connecting the inner ends of the levers together, means pivotally connecting the outer ends of the levers to the bolts, an operating arm, means for sliding the arm from the inside of the door, an operating rod connected with the lever connecting means and arranged to extend through the inner edge of the door, and a casing formed in the door frame, a cover for the casing, a lock for the cover, partition plates disposed in the casing, means disposed between the partition plates for engaging said operating bar for actuating said bolts and a hinged panel secured to one of said partitions for hiding said means between said partition plates.

4. The combination with a door and a door frame, of a lock for the door including a pair of reciprocating bolts, means normally urging the bolts into locking position, a pair of operating levers pivotally secured at a point intermediate their ends to the door, means pivotally connecting the levers at their outer ends to the bolts, an operating body connecting the levers together at their inner ends, an operating arm carried by the door, means for operating the arm from the inside of the door, an operating rod connected with the levers and arranged to extend through the hinge edge of the door into the door frame, a casing formed in the door frame adjacent to the hinge edge of the door, an operating bolt arranged to extend through the casing into engagement with the operating bar, a knob for operating said operating bolt, and a hinge panel for the casing for hiding the operating bolt and knob from view.

5. The combination with a door frame and a door, of a lock therefor comprising a locking bolt arranged to be normally projected into engagement with the door frame, an operating knob carried by the door and arranged on the inner face thereof for operating the bolt, and means arranged within the frame of the door at the outer side thereof for operating said bolt.

6. The combination with a door frame and a door hingedly connected thereto, of a lock for the door including a locking bolt adapted to be normally projected into engagement with the door frame, means for operating the bolt, and a plate slidably carried by the

free edge of the door adapted to be moved over the bolt to normally hold the same against operation.

7. The combination with a door frame and a door hingedly connected thereto, of a lock for the door including a bolt adapted to be normally projected into engagement with the door frame, means for operating

the bolt, a sliding plate carried by the free edge of the door having an opening therein through which the bolt is adapted to project, and means for including a knob for sliding the plate for moving said opening into and out of alignment with the bolt.

In testimony whereof I affix my signature.
JOHN PENCE POWELLS.
